UNITED STATES PATENT OFFICE.

EVERETT E. GRAY, OF LOS ANGELES, CALIFORNIA, ASSIGNOR TO SOPHIA PEARL BLOOMFIELD, OF LOS ANGELES, CALIFORNIA.

DESIGN FOR A CABINET.

Application filed October 21, 1922. Serial No. 4,050. Term of patent 14 years.

To all whom it may concern:

Be it known that I, EVERETT E. GRAY, a citizen of the United States, residing at Los Angeles, in the county of Los Angeles and State of California, have invented a new, original, and ornamental Design for Cabinets, of which the following is a specification, reference being had to the accompanying drawing, forming part thereof.

The figure is a perspective view of a cabinet, showing my new design.

I claim:

The ornamental design for a cabinet, as shown.

EVERETT E. GRAY.
